UNITED STATES PATENT OFFICE.

MORRIS FROELICH, OF CHICAGO, ILLINOIS.

DESIGN FOR A ROTARY OVEN.

54,075.

Specification for Design.

Patented Nov. 4, 1919.

Application filed June 21, 1919. Serial No. 305,905. Term of patent 14 years.

To all whom it may concern:

Be it known that I, MORRIS FROELICH, a citizen of the United States, residing at Chicago, in the county of Cook and State of Illinois, have invented a new, original, and ornamental Design for a Rotary Oven, of which the following is a specification, reference being had to the accompanying drawing, forming part thereof.

The figure is a perspective view of a rotary oven showing my new design.

I claim:

The ornamental design for a rotary oven, as shown.

MORRIS FROELICH.

Witnesses:

ROY W. HILL,

CHARLES I. COBB.
